UNITED STATES PATENT OFFICE.

RALPH A. LEWIS, OF GRANGEVILLE, IDAHO.

ROCKING-CHAIR.

1,348,429.

Specification of Letters Patent. Patented Aug. 3, 1920.

Application filed June 30, 1919, Serial No. 307,553. Renewed May 15, 1920. Serial No. 381,748.

To all whom it may concern:

Be it known that I, RALPH A. LEWIS, a citizen of the United States, residing at Grangeville, in the county of Idaho and State of Idaho, have invented certain new and useful Improvements in Rocking-Chairs, of which the following is a specification, reference being had to the accompanying drawings.

10 This invention relates to an improved rocking chair, and particularly the kind provided with an adjustable swinging back and an adjustable leg and foot rest.

One of the objects of the invention is to 15 provide a rocking chair having suitable bracing means between the seat and the legs and between the legs and the rockers, the bracing means between the seat and the legs consisting of inner and outer metallic straps, 20 which are extended far enough downwardly as to overlie the rockers, thereby reinforcing the legs relatively to the rockers.

A further object of the invention is the 25 provision of bracing means between the forward edges of the rear legs and the seat, which consist of metallic sheet straps, arranged angularly.

A further object of the invention is the 30 provision of an adjustable swinging leg and foot rest, hingedly mounted on the forward edge of the seat and provided with pivoted supporting members which adjustably extend through openings of the front legs and are provided with notches, to engage the 35 lower edge of openings or slots in face plates of the forward parts of the front legs, to hold the combined leg and foot rest in different adjusted positions.

A further object of the invention is the 40 provision of arm rests, supporting braces therefor, whereby the arm rests are supported rigidly in position.

A further object of the invention is the 45 provision of angularly arranged bracing means between the rear supporting braces for the arm rests, and which have bent parts which are adjacent to the elongated slots in the rear supporting braces for the arm rests, in combination with toothed means pivotally 50 carried by the swinging back engaging through the elongated slots, to coöperate with the bent portions of the angularly arranged braces to support the back at different inclinations relatively to the seat.

55 While the design and construction at present illustrated and set forth is deemed

preferable, it is obvious that as a result of a reduction of the invention to a more practical form for commercial purposes, the invention may be susceptible to changes, and 60 the right to these changes is claimed, provided they are comprehended within the scope of what is claimed.

The invention comprises further features and combination of parts, as will be herein-after set forth, shown in the drawings and 65 claimed.

In the drawings:

Figure 1 is a perspective view of the improved rocking chair constructed in accordance with the invention, showing the adjustable swinging leg and foot rest detached. 70

Fig. 2 is a view in side elevation of the rocking chair, showing the swinging back and swinging leg and foot rest in different 75 adjusted positions in full lines and in dotted lines.

Fig. 3 is a detail perspective view of a portion of the combined leg and foot rest, showing the connection between one of the 80 toothed supporting members with the leg and foot rest.

Referring to the drawings, 1 designates the seat of the chair and secured to the bottom of the seat adjacent its forward and rear edges are cleats 2 and 3. Depending from the ends of the cleats 2 and 3 are the forward and rear legs 4 and 5. Secured adjacent the outer side faces of the legs as at 6 are metallic straps or strips 7, the lower 85 ends of which are secured at 8 to the outer side faces of the rockers 9. Arranged between the forward edges of the rear legs 5 and the bottom of the seat are the angularly 90 arranged braces 10, which act to further reinforce the rear legs. 95

Secured to the inner faces of the forward legs 4 are metallic straps 11, and the lower ends of these straps are secured at 12 to the inner faces of the rockers 9. Beyond the 100 upper securing means of the straps 11, said straps are bent to provide the diagonal braces 13, which extend toward the under face of the cleat 2 and are provided with extensions 14, which overlie each other, and 105 are secured to the seat, thereby additionally reinforcing the front legs relatively to the seat. In order to further reinforce the seat and the legs angular braces 15 are secured to the cleat and the inner adjacent faces of 110 the legs.

Secured to the inner adjacent faces of the

rear legs 5 are metallic straps 16, the lower ends of which are secured to the inner faces of the rockers 9. The upper parts of the straps 16 are diagonally inclined toward each other to provide the braces 17. The upper ends of the braces 17 have extensions 18 which overlie each other and are secured in any suitable manner to the under face of the seat 1. By means of the straps 16 and their braces 17, the rear legs are additionally reinforced relatively to the cleat 3. The lower ends of the straps 16 are secured to the inner adjacent faces of the rockers 9.

The forward legs 4 are provided with slots or openings 19, and secured to the front faces of the legs 4 are face plates 20 provided with slots or openings 21. Hingedly connected as at 22 adjacent the forward edge of the seat 1 of the chair is a combined leg and rest 23. Carried by the rear or bottom face of the leg rest 23 are plates 24 to the ears of which the supporting bars 25 are pivotally connected as shown at 26. These supporting bars have their free end portions slightly curved and formed in their edges are teeth 27. The supporting bars 25 engage through the slots 21 and through the openings 19, so that the teeth 29 may engage the lower edges of the openings or slots 30 of the plates 20, so as to hold the combined leg and foot rest in different adjusted positions as shown in full lines and in dotted lines in Fig. 2. Supporting braces 28 which are rectangular as shown and constructed of single pieces of sheet metal, are secured at 29 and 30 to the upper face of the seat 1. Diagonal braces 31 are also secured at 30, and are in turn secured at 32 to the rear legs of the supporting braces 28. Beyond where the braces 31 are secured at 32 said braces terminate in offset extensions 33, which are positioned adjacent the elongated slots 34 of the rear legs of the supporting braces 28.

Hingedly connected at 35 to the rear edge of the seat 1 is an adjustable swinging back 36 having side flanges 37. Angular plates 38 are secured to the rear face of the back 36 and the edges of the back, and pivoted to said angle plates as shown at 39 are supporting bars 40, which engage through the slots 34. The lower edges of the bars 40 are provided with teeth 41, any opposite two of which are designed to engage the offset portions or extensions 33 of the members 31 for the purpose of holding the back 36 in different inclined positions relatively to the seat, as shown in full lines and dotted lines in Fig. 2. The forward ends of the bars 40 have connected thereto handles 42, whereby the bars 40 may be easily manipulated in order to adjust the back 36. Secured to the inner adjacent faces of the rear legs and the under face of the rear cleat 3 are angle braces 44, to additionally reinforce the rear legs 5 relatively to the cleat 3. Secured upon

the supporting braces 28 in any suitable manner are arm rests 45. The arm rests 45 may be provided with cushions of any suitable construction. The seat 1 and the back may also be provided with cushions (not shown) of any suitable construction. By positioning the leg and foot rest 23 in a raised position as shown in full lines and lowering the back as shown in full lines an occupant may lie at full length in the chair. By leaving the leg and foot rest as shown in full lines and adjusting the back as shown in dotted lines the body of the occupant may rest in an inclined position. By lowering the leg and foot rest as shown in dotted lines the legs below the knee may be arranged in inclined positions. As shown in Fig. 1, with the back raised to almost a perpendicular position relatively to the seat, the chair may be used as an ordinary rocker. The combined leg and foot rest is provided with notches 46, which are designed to engage the forward part 6 of the rockers, when the rest is lowered.

The invention having been set forth, what is claimed as new and useful is:

1. In a rocking chair, the combination with a seat, of cleats secured to its under face near its forward and rear edges, depending legs connected to the cleats near their ends, rockers connected to the lower ends of said legs, bracing means between the under face of the cleat and the inner faces of the legs and the rockers, bracing means between the outer side faces of the legs and the seat and the rockers, and bracing means between the forward edges of the rear legs and the seat.

2. In a rocking chair, the combination with a seat provided with supporting legs having rockers, of a back hingedly connected to the rear edge of the seat, arm rest supporting braces, each being constructed from a single strip of sheet metal, bent rectangular and mounted upon the seat, the rear legs of the supporting braces having elongated slots, diagonal braces for the rear legs of the supporting braces, said diagonal braces having offset extensions adjacent the slots of the rear legs of the supporting braces, and means pivotally connected to the back and passing through the slots to engage the offset extensions to hold the back in different adjusted positions.

3. In a rocking chair, the combination with a seat provided with supporting legs having rockers, of a back hingedly connected to the rear edge of the seat, arm rest supporting braces, each being constructed from a single strip of sheet metal bent rectangular and mounted upon the seat, the rear legs of the supporting braces having elongated slots, diagonal braces for the rear legs of the supporting braces, said diagonal braces having offset extensions adjacent the slots of the rear legs of the supporting braces, and bars

pivots connected to the side edges of the back and passing through the slots of the rear legs of the supporting braces and having teeth to coöperate with the offset ⁵ tensions to hold the back in different adjusted positions, and handles carried by said bars.

In testimony whereof I hereunto affix my signature in the presence of two witnesses.

RALPH A. LEWIS.
